[57] CLAIM

The ornamental design of an electric pipe threader and pipe clamp combination, substantially as shown and described.

DESCRIPTION

FIG. 1 is a perspective view of a electric pipe threader and pipe clamp combination showing my new design with the pipe and electric cord being shown in broken lines for illustrative purposes only;

FIG. 2 is a side elevational view thereof;

FIG. 3 is an opposite side elevational view thereof;

FIG. 4 is a front end elevational view thereof;

FIG. 5 is a rear end elevational view thereof;

FIG. 6 is a top plan view thereof;

FIG. 7 is a bottom plan view thereof.
